UNITED STATES PATENT OFFICE.

ALEXANDER R. KELTIE, OF BOSTON, MASSACHUSETTS.

HANDPIECE FOR DENTAL ENGINES.

1,056,341.

Specification of Letters Patent. Patented Mar. 18, 1913.

Application filed December 4, 1911. Serial No. 663,846.

To all whom it may concern:

Be it known that I, ALEXANDER R. KELTIE, a citizen of the United States, and resident of Boston, in the county of Suffolk and State of Massachusetts, have invented certain new and useful Improvements in Handpieces for Dental Engines, of which the following is a specification:

The invention relates to improvements in handpieces for dental engines, and more particularly to the angle attachment disclosed in Patent No. 522,291, granted July 3, 1894, to C. H. Davis.

It has for its object to simplify and cheapen the construction without detracting from the efficiency of the device.

The invention consists in the novel construction, combination and arrangement of parts, hereinafter described, pointed out in the appended claim, and illustrated in the accompanying drawings.

In the drawings, in which similar reference characters designate corresponding parts, Figure 1 is a side elevation, partly in section and broken away in parts, of an attachment embodying the invention. Fig. 2 is a sectional view of the angle-head and end of the casing, the operating parts being removed. Fig. 3 shows end and side views of the angle-head. Fig. 4 is a sectional view on the line 4—4 of Fig. 1. Fig. 5 shows edge and plan views of the screw-ring for holding the angle-head and casing in rotatable connection. Fig. 6 is a detail view of the bur-holder and driving gear. Fig. 7 shows the upper end of the bur. Fig. 8 is a detail view of one of the gear-wheels.

In one end of the cylindrical holder 1 is secured the tubular casing 2 by the screw 3 passing through the holder and casing. In the tubular casing is the shaft 4 journaled in the bearing sleeve 5 interposed between the shaft and the casing. The inner end of the shaft 4 extends into the holder 1 and is flattened, as at 6, to form the driving connection with the flexible shaft inserted in the end of the holder. On the outer end of the shaft 4 is the head 7 rotatable in the outer end of the tubular casing 2 and abutting the outer end of the bearing-sleeve 5.

The latter by abutting the head 7 prevents longitudinal movement of the shaft within the tubular casing. On the crown of the head 7 is the bevel-gear 8.

On the outer end of the tubular casing 2 is the annular neck 9 bent at an angle to the

main direction of casing. At the edge of the annular neck is the flange 10 (Fig. 2). In the angular bend between the main casing 2 and the annular neck 9 is the partition 11 extending across the interior of the casing. In one side of this partition is an opening 12 through which an edge of the bevel-gear 8 projects into the compartment formed by the annular neck 9. From the partition 11 projects the stud 13 concentrically into the chamber formed by the annular neck. On the stud 13 is journaled the double gear-wheel 14 (Fig. 8) having on one face the bevel-gear 15 meshing through the opening 12 in the partition 11 with the bevel-gear 8 on the shaft 4, and on the other face is the bevel-gear 16 extending beyond the annular neck 9. The back edge of the bevel-gear 16 bears on the end of the annular neck 9, which prevents a crowding together of the gears 15 and 8.

Rotatably adjustable on the outer end of the tubular casing 2 is the angular head 17. In one arm 18 of this head is screw-threaded the retaining ring 19 (Fig. 5) journaled on the annular neck 9 inside of the flange 10. This ring is cut, as at 20, so that it can be sprung over the annular neck back of the flange preliminary to being screwed into the arm 18. The ring 19 not only serves to hold the angular head in place on the outer end of the shaft 4, but by turning on the neck 9 also forms a bearing whereby the angular head can be rotatably adjusted on the tubular casing.

The angular head 17 is held in its adjustment on the tubular casing 2 by the spring pawl 21. The latter lies in the longitudinal groove 22 in the casing with its inner end 95 extending under the cylindrical holder 1 and thereby held in place. The free end of the pawl, when depressed, engages the teeth 23 on the end of the arm 18 of the angular head. The pawl toward its free end, as at 24, is thickened so as to project above the surface of the tubular casing. Slidable on the tubular casing is the ring 25, which when moved outwardly engages the thickened part of the pawl and holds the latter in engagement with the teeth 23. With the pawl 21 in engagement with the teeth 23 and the ring 25 pressed outwardly on the thickened part 24 of the pawl, the angular head is locked in the position to which it is adjusted on the tubular casing.

Into the outer end of the arm 26 of the

angular head 17 is screwed the cap 27. Journalized at its outer end in this cap is the sleeve 28 (Fig. 6) with its inner end extending into the top of the arm. On the inner 5 end of the sleeve is the collar 29 journalized in the bearing 30 (Fig. 2) in the upper part of the arm 26. This collar not only forms a rotatable bearing for the inner end of the sleeve, but also serves to take up the inward thrust of the sleeve. In the extreme inner end of the sleeve is the flattened part 31, the purpose of which will be explained further on. Fixed on the sleeve 28 just inside of the cap 27 is the bevel-gear 32 meshing 15 with the bevel-gear 16 of the double gear-wheel 14. The back of the bevel-gear 32 bearing against the cap 27 forms a stop to prevent the outward movement of the sleeve through the cap.

20 The shank of the grinding bur 33 fits the sleeve 28 and its inner end is notched, as at 34 (Fig. 7), to fit the flattened part 31 of the sleeve 28 so that when the sleeve is turned the bur will be rotated with it. At 25 the end of the shank is the annular groove 35 with which engages the latch 36. The latter is slideable in recess 37 (Fig. 3) in the angular head 17, being pivoted therein by the pin 38 (Fig. 4). The catch has a projecting lip 39 so that it can be readily opened after being closed. With the latch in engagement with the groove 35 in the shank of the bur, the latter will be held in place within the sleeve 28 while the latter is rotated.

30 In operation, the bur 33 having been secured in the sleeve 28, the angular head 17 having been adjusted on the tubular casing 2 to the angle required by the work, and the attachment connected with the usual flexible shafting, on the application of power the shaft 4 is rotated and through the meshing bevel-gears 8 and 15 the double gear-wheel 14 is driven. Through the meshing bevel-gears 16 and 32 motion is transmitted

from the double gear-wheel 14 to the sleeve 45 28 and the bur 33 is thereby driven irrespective of the position of the angular head 17 with relation to the tubular casing 2.

Having thus described my invention, what I claim and desire to secure by Letters Patent is:

In an angle attachment for dental engines, a tubular casing, an annular neck on the end of the casing bent at an angle to the longitudinal direction of the casing, a partition 55 in the casing at the bend between the casing and neck, said partition having an opening in one side, a shaft journalized in the casing, a bevel-gear on the shaft projecting through the opening in the partition, a stud on the 60 partition projecting concentrically into the annular neck, a wheel journalized on the stud having a bevel-gear on one end meshing with the bevel-gear projecting through the partition and said wheel having a bevel-gear 65 on its other end projecting beyond the annular neck with the back of the last mentioned bevel-gear riding on the end of the annular neck, an angular head having its inner arm journalized on the annular neck 70 and its outer arm provided with a bearing in its inner end, a sleeve journalized in the outer arm of the angular head having a flattened portion at its inner end adapted to receive the flattened end of a dental bur inserted in said sleeve, a collar on the sleeve 75 journalized in the bearing in the inner end of the outer arm of the angular head, and a latch pivoted in the angular head adapted to engage the groove at the inner end of the bur inserted in said sleeve.

In testimony whereof I hereunto affix my signature in the presence of two witnesses.

ALEXANDER R. KELTIE.
